US0D1059129S

(12) United States Design Patent (10) Patent No.: US D1,059,129 S
(45) Date of Patent: * Jan. 28, 2025

(54) TRAY

(71) Applicant: Dongguan Mengyang E-commerce Co., Ltd., Dongguan (CN)

(72) Inventor: Xiaofang Li, Dongguan (CN)

(73) Assignee: Dongguan Mengyang E-commerce Co., Ltd., Dongguan (CN)

() Term: 15 Years

(21) Appl. No.: 29/963,556

(22) Filed: Sep. 18, 2024

(30) Foreign Application Priority Data

Jun. 4, 2024 (CN) 202430340228.X

(51) LOC (15) Cl. 07-01
